COMBINATION CORNER AND CHALK HOLDER FOR BILLIARD TABLE OR THE LIKE

George J. Kolivera, Chicago, Ill.

Application May 9, 1950, Serial No. 9,832

Term of patent 3½ years

(Cl. D34—3)

To all whom it may concern:

Be it known that I, George J. Kolivera, a citizen of the United States, residing at Chicago, in the county of Cook and State of Illinois, have invented a new, original, and ornamental Design for a Combination Corner and Chalk Holder for Billiard Table or the like, of which the following is a specification, reference being had to the accompanying drawing, forming part thereof.

In the drawing:

Figure 1 is a perspective view of a combination corner and chalk holder for billiard table or the like, showing my new design;

Figure 2 is a plan view of the same;

Figure 3 is a bottom view of the same;

Figure 4 is a side elevational view of the same; and

Figure 5 is a view taken in section on the line 5—5 of Figure 2.

I claim:

The ornamental design for a combination corner and chalk holder for billiard table or the like, as shown.

GEORGE J. KOLIVERA.
